UNITED STATES PATENT OFFICE.

LEE H. PARKER, OF BOSTON, MASSACHUSETTS, ASSIGNOR TO SPRAY ENGINEERING COMPANY, OF BOSTON, MASSACHUSETTS, A CORPORATION OF MASSACHUSETTS.

SPRAY-NOZZLE.

1,309,597.

Specification of Letters Patent.

Patented July 8, 1919.

Original application filed December 1, 1917, Serial No. 204,962. Divided and this application filed March 1, 1919. Serial No. 280,048.

To all whom it may concern:

Be it known that I, LEE H. PARKER, a citizen of the United States, and a resident of Boston, in the county of Suffolk and State 5 of Massachusetts, have invented an Improvement in Spray-Nozzles, of which the following description, in connection with the accompanying drawings, is a specification, like characters on the drawings representing 10 like parts.

This application is a division of my co-pending application Serial No. 204,962, filed December 1, 1917.

This invention relates to spray nozzles of 15 general application and may be used for distributing liquids containing more or less solid matter.

While my invention is not restricted to such use, an important object thereof is to 20 provide a nozzle for cooling water in or in connection with cooling ponds or for condensers, ice plants, mills or any industry requiring a supply of cooling water or liquid.

By the nozzle herein described I form and 25 distribute over preferably an extended area a spray composed of or comprising water or other liquid or suitable fluid, and in accordance with the disclosed and preferred embodiment of my invention, I discharge the 30 liquid in a spray that is of substantially uniform homogeneity throughout. Such a spray may be used in any of the defined relations or for any other suitable purpose, as, for example, for spraying effluent, for precipitating or for spraying coal dust or other 35 foreign matter, for air washing, for condensing vapors, for humidifying air and for other purposes. In carrying out my invention, I project the fluid in a flaring spray and 40 within the nozzle I preferably simultaneously produce an inner jet and one or more surrounding jets which are preferably and for the best results mixed within the mixing chamber, so that there is effective mixture 45 or blending of the jets before they issue in spray form from the mixing chamber, which latter may be and preferably is so shaped or is provided with means whereby to cause impact and mixing of the several jets within 50 the confined space of the mixing chamber of the nozzle.

In order that the principle of the invention may be readily understood, I have in the accompanying drawing disclosed a single

type of nozzle embodying my invention and 55 wherein—

Figure 1 is a vertical, central section of such nozzle;

Fig. 2 is a view upon the line 2—2 of Fig. 1 looking downward or with the cap portion 60 of the nozzle removed; and

Fig. 3 is a transverse section upon the line 3—3 of Fig. 1.

Referring more particularly to the drawing, the nozzle herein shown comprises a 65 shell or casing 1, the lower end of which is adapted to be attached to a hose or pipe for conveying the water or other liquid. To that end, I have herein represented said shell or casing 1 as threaded at its lower end at 2. 70 Preferably also the upper end of the shell or casing 1 is threaded as represented at 3 for the reception of the head or cap 4 of the nozzle, which is interiorly threaded. My invention is, however, not limited to a nozzle 75 wherein the parts 1 and 4 are separate or detachable, since they might be formed in a single piece. Preferably, for convenience in manufacture, the members 1 and 4 are detachable. 80

The head or cap 4 is provided with a suitable discharge orifice 5 herein represented as circular. The interior of the head or cap 4 constitutes a mixing chamber, and it may be and preferably is tapering or more or less 85 dome shaped, so that the streams of liquid are caused to mix and intermingle prior to their discharge from the outlet 5. In the patent to Eneas, No. 1,101,264, dated June 23, 1914, there is disclosed a spray nozzle 90 having a central, axially arranged sleeve or tube through which the central or axial jet passes, surrounding spiral or inclined vanes being provided to convey a plurality of 95 streams of liquid in spiral directions, all of the streams being caused to meet and intermingle within the mixing chamber.

It is the purpose of my invention to provide means for supplying liquid interiorly of the surrounding and preferably spiral or 100 inclined jet or jets, and I have for this purpose herein represented a single inner passage for providing an inner jet, at least a portion of such passage being eccentric to the longitudinal axis of the nozzle. The 105 surrounding jet or jets may be of any suitable character. Preferably the surrounding jet or the plurality of surrounding jets, if

employed, are formed by reason of the provision of spirals or inclined formations which may be of any suitable character. I do not provide a tube or sleeve for the 5 inner jet but omit the physical tube or sleeve or other element defining the circumferential boundary of the inner jet or stream, which, as above stated, is eccentrically located throughout at least a portion of its 10 extent with respect to the longitudinal axis of the nozzle.

Preferably I obtain the inner jet or stream by positioning or forming the vanes or spirals or other elements by which the 15 surrounding jet or jets are formed in such manner as to permit the passage of the inner jet. In the disclosed embodiment of my invention, I have accomplished this result by inwardly terminating the vane or vanes at 20 suitable distances radially from the axis of the nozzle, so as to leave an unobstructed non-axial passage through which the liquid passes in a straight stream. I may, however, form or shape or position the vane 25 or vanes in any equivalent way permitting the liquid to pass non-axially between them and non-axially within the convolutions of the vane, if a single vane only be employed. In accomplishing the result in this particular 30 form of the invention I provide a plurality of spirals or inclined vanes 6 of any suitable pitch and of any suitable radial extent. I have herein represented said spirals as cast or otherwise formed within 35 the shell or casing 1, but within the scope and purpose of my invention, they may be separately formed and attached thereto in any suitable manner or positioned frictionally or otherwise within the nozzle. 40 Preferably the said spirals or inclined vanes terminate at or below the upper end of the shell or casing 1; that is, at or below the base of the mixing chamber, so that the liquid is discharged from the upper ends 45 of the spirals or inclined vanes directly against the inner wall 7 of the mixing chamber, and in such a manner that the stream or streams, which are outwardly thrown under centrifugal force, are guided 50 by the inner surface 7 across the discharge opening 5 where or below which they meet the herein disclosed inner jet, indicated at 8, with the result that all the jets are thoroughly mixed or intermingled within the 55 mixing chamber, and so that they issue therefrom in a flaring spray of substantially uniform homogeneity in cross section. Preferably each of the spirals or inclined vanes 6 at its lower end merges into the inner 60 surface 9 of the shell or casing 1, as indicated, and at the upper end each of said spirals or vanes again merges into the inner wall of the shell or casing, as indicated at 11, thus presenting as little obstruction as 65 possible to the spiral or inclined streams,

particularly at the lower end thereof. In other words, the spiral or spirals or inclined vanes 6 taper toward or are of gradually decreasing width at the points where they merge into the upper surface of the 70 shell 9. Within the broad scope and purpose of my invention, however, they may be of full width at both their upper and their lower ends or of any suitable intermediate widths. I may employ my invention 75 in the spraying of sewage which contains more or less solid matter, and I may and preferably in such case so construct the spiral or spirals that they present the least resistance to the flow of the material 80 while preserving the flow of material in a single stream and herein an inner non-central jet.

While the liquid or other suitable material that is to be delivered through the 85 nozzle within the surrounding or spiral jet or jets may be caused to flow in any suitable manner, I have herein represented means for providing for the flow of the liquid or other material in a single inner 90 stream, and as shown most clearly in Figs. 1 and 3, I have provided means whereby at least the portion of the flow that is nearest the intake end of the nozzle is located at one side of or eccentrically of the longitudinal axis of the nozzle. To this end, I have in said Figs. 1 and 3, represented the vane or vanes 6 as so formed as to provide an opening or passage 12 whereby liquid entering the nozzle is conducted to one side 95 of the longitudinal axis of the nozzle, and after passing through the opening 12, in this embodiment of my invention, is permitted or caused, before entering the mixing chamber 8, to become substantially axial. 100 This I have accomplished, in this embodiment of my invention, by providing a substantially axial passage or opening 13 prior to or as herein indicated at the point where the liquid enters the mixing chamber. 110

Desirably and in the disclosed embodiment of my invention, the diameter of the inner opening 12 herein shown is at least substantially one third the diameter of the vane or vanes 6, and it is also substantially equal to 115 the full diameter of the outlet 5 from the nozzle. This permits the ready use of the nozzle with a liquid containing solid matter, such as sewage. The dimensions which I have given are illustrative merely, and it is 120 clearly to be understood that my invention is in no sense limited thereto as the dimensions of parts may be such as to provide in any equivalent manner for the onward flow of liquid substantially parallel to but eccentric to the longitudinal axis of the nozzle. 125

In order further to decrease the obstruction presented by the spirals or vanes 6, the inner edge 12' thereof is made rounding in cross section, as clearly indicated in Fig. 1. 130

Preferably each of the vanes or spirals 6 is made of a decreasing pitch, so that the surrounding jet or jets are brought gradually from a flow in the direction of the entering stream to a flow in a direction at approximately right angles to the stream flow and approximately tangential thereto. Thus, the surrounding jet or jets are with the least possible obstruction brought into a direction of flow so as thoroughly to mix and intermingle with the inner stream. The inner flow, by which I mean the flow of material otherwise than along and as directly caused by the vanes or spirals 6, is preferably straight, though within the scope and purpose of my invention, it may be rotatory in whole or in part. The cylindrical surface of the inner flow may have more or less of a rotatory motion which may be caused in part by the effect of the surrounding jet or jets which are not separated from the inner flow by a physical wall. The outer or surrounding jet or jets partake of their described paths, particularly through centrifugal action, but the inner flow is not under the influence of centrifugal action and maintains a substantially straight course into the mixing chamber 8.

In the said mixing chamber, the inner flow meets the surrounding jet or jets, and thus the liquid or fluid of the jets is mixed or blended within a confined chamber or space. The mixed mass issues from the chamber in a spray which is of substantially uniform homogeneity throughout. While the several jets or streams are mixed within the mixing chamber 7 substantially as set forth in the said patent to Eneas, No. 1,101,264, I have found in practice that the described provision of means for effecting the formation of an inner flow and one or more surrounding jets peculiarly coöperates with the mixing chamber, and particularly in that the liquid from all the jets enters with a minimum of obstruction into the mixing chamber and in streams of such unimpeded force as to result in an even, more effective mixing than before. Moreover I find that in some cases there is or may be a preliminary mixing at the very base of and within the mixing chamber, that is, at substantially the point where the several streams enter thereto. This is owing to the fact that no physical wall is present so as accurately or exactly to define the shape or radial extent of the inner flow. Within the scope and purpose of my invention, the mixing chamber need not be employed, although it preferably and for the best results is employed.

Referring to the disclosed type only of my invention, I point out that the inner flow is herein illustrated as a jet that is in the direction of the longitudinal axis of the nozzle and throughout a portion of its length is eccentric to the said longitudinal axis; that is, it is herein shown as non-axial, particularly at a portion thereof between the mixing chamber and the liquid entrance end of the nozzle. In the present embodiment of my invention, the vane or vanes 6 are so shaped that only throughout a portion of the length of the inner flow does the liquid pass axially, thus forming a central jet. Still referring to the disclosed embodiment of my invention, the remainder of the length of the passage or space wherethrough passes the liquid forming the inner flow is non-axial. In the disclosed embodiment of my invention, at the upper portion of the inner flow, the course of the liquid is substantially central or axial of the passage.

Again referring to the disclosed embodiment of the invention, I have herein so constructed the nozzle that the liquid does not, immediately where it enters the nozzle, partake of a central stream character, but it does do so before the mixing chamber is reached. This depends upon the shape and position and construction of the vane or vanes.

Referring to that portion of the nozzle where the eccentrically located opening 12 is provided, it will be apparent that the portion 14 of the vane 6 adjacent thereto constitutes in effect a central plug or obstruction of restricted length, and at a suitable point whereabove the liquid partakes of the central stream character, to which feature, however, my invention is not limited.

In other words, I have at 14 indicated a central or axial obstruction, and the opening 12 is at one side thereof. Such opening is preferably of the same diameter as the exit passage 5.

While my invention is in no sense whatever limited to such proportioning of the parts, it is pointed out that for the best results and particularly where the nozzle is used in the spraying of sewage or in the spraying of liquid containing more or less solid matter, the inner formation providing for the inner flow is approximately one third of the diameter of the entire passage through the nozzle.

The surrounding or outer jet or jets may be of any suitable character. While I preferably use a spiral vane or vanes, such as indicated at 6, it is clear that the vane or vanes need not be of spiral character, so long as it or they are substantially a surrounding or outer vane or vanes, so as to produce an outer or surrounding jet or jets.

The formation or structure of the nozzle interiorly of the shell 1 constitutes a core mainly made up of vanes or spirals 6 and also including the prolongation or lateral formation of one of the vanes 6 indicated at 14 in Fig. 1, and which constitutes an obstructing formation shielding the outlet of the nozzle from the direct projection or travel of an axial portion of the initial

stream of liquid through the nozzle. The construction is such that there is permitted an onward projection or travel laterally of the axis of the nozzle of liquid admitted at 5 the inlet of the nozzle axially of said nozzle.

It will be noted that the core includes the formation of a vane or vanes, a central obstructing formation, and also a formation permitting the forward projection or travel 10 of a portion of the liquid stream as clearly shown at 12 in Fig. 3.

The formation 14 is positioned across the axis of the nozzle, and at 12 is the liquid passage or opening, which, as clearly shown 15 in Fig. 3, is the result of a vane-edge shape or formation of the vane or vanes, such passage or opening being laterally offset from the axis of the nozzle. This opening or passage resulting from said vane-edge formation 20 permits forward projection or travel of a portion of the liquid stream. This passage or opening resulting from the vane-edge formation modifies the flow of liquid along the vane wherein it is formed. That is to say, it modifies the rate of spiral advancement 25 imparted to a portion of the liquid along said vane. The said passage or opening resulting from said vane-edge formation causes a part of the initial liquid stream 30 to exert liquid pressure directly longitudinally of the nozzle, and thereby accelerates the rate of spiral advancement of a portion of such initial stream. The core construction 35 is such as to impart a plurality of different movements to different portions of the initial stream. The core formation is such as to cause different portions of a single and imperforate stream of liquid to impact upon each other and upon the interior of 40 the housing of the nozzle, so as to convert the liquid stream into a spray of substantially uniform consistency. The said core formation includes a spiral or helical passage and an opening laterally offset from 45 the axis of the nozzle.

I have heretofore pointed out that the spirals 6 are represented as cast or otherwise formed within the shell or casing 1, but that 50 within the scope and purpose of the invention, they may be separately formed and attached thereto in any suitable manner or positioned frictionally or otherwise within the nozzle. Such removability permits the cleaning upon removal of the core.

55 It will be observed that the vane-edge shape or formation resulting in the opening 12 affords the equivalent of a bore extending through the nozzle core in a direction substantially parallel with the axis of 60 the nozzle.

Having thus described one illustrative embodiment of my invention, I desire it to be understood that although specific terms are employed, they are used in a generic and 65 descriptive sense and not for purposes of

limitation, the scope of the invention being set forth in the following claims.

Claims:

1. A spray nozzle having a housing with an inlet and an outlet, and means within the 70 housing for imparting spirally advancing motion to parts of a liquid stream, with means shielding the outlet from the direct projection or travel of an axial portion of the initial stream of liquid therethrough but 75 permitting onward projection or travel, laterally of the axis of the nozzle, of liquid admitted at the inlet of the nozzle axially thereof, the nozzle being devoid of a physical wall separating the spirally advancing parts 80 of the liquid stream from the remainder thereof.

2. A spray nozzle having a housing with an inlet and an outlet and one or more vanes within the housing for imparting spirally 85 advancing motion to parts of a liquid stream, together with a formation integral with said vane or vanes, for preventing the direct projection or travel of an axial portion of the initial stream of liquid therethrough, but 90 permitting onward projection or travel, laterally of the axis of the nozzle, of liquid admitted at the inlet of the nozzle axially thereof, the nozzle being devoid of a physical wall separating the spirally advancing 95 parts of the liquid stream from the remainder thereof.

3. A spray nozzle having a housing with an inlet and an outlet and one or more vanes within the housing for imparting spirally 100 advancing motion to parts of a liquid stream, there being an opening laterally offset from the axis of the nozzle, for the forward projection or travel of a portion of the liquid stream, the nozzle being devoid of a physical wall separating the spirally advancing 105 parts of the liquid stream from the remainder thereof.

4. A spray nozzle having a housing with an inlet and an outlet and a vane within the 110 housing for imparting spirally advancing motion to a part of a liquid stream, said vane having a liquid passage laterally offset from the axis of the nozzle, for the forward projection or travel of a portion of the liquid 115 stream, said housing having a spray producing chamber in advance of said vane, the nozzle being devoid of a physical wall separating the spirally advancing parts of the liquid stream from the remainder thereof. 120

5. A spray nozzle having a housing with an inlet and an outlet and a vane within the housing for imparting spirally advancing motion to a part of a liquid stream, said vane having a vane-edge shape or formation 125 providing a passage laterally offset from the axis of the nozzle for the forward projection or travel of a portion of the liquid stream, said housing having a mixing chamber in advance of said vane and from which 130

- the liquid is discharged through said outlet as a spray of substantially uniform homogeneity throughout.
6. A spray nozzle with inlet and outlet and having a vane equipped with a vane-edge shape or formation laterally offset from the axis of the nozzle and providing a passage for liquid toward said outlet and modifying the flow of liquid along said 10 vane.
7. In a nozzle, a spiral vane having its inner edge equipped with a vane-edge shape or formation laterally of the axis of the nozzle for modifying the rate of spiral advancement imparted to a portion of the liquid along the vane.
8. In a nozzle, a spiral vane having its inner edge equipped with a vane-edge shape or formation laterally offset from the axis 20 of said nozzle, and acting to modify the rate of spiral advancement imparted to a portion of the liquid along said vane.
9. In a liquid manipulating appliance, means tending to produce an initial stream 25 developing a spirally advancing jet, and means laterally offset from the longitudinal axis of the nozzle for causing a part of said stream to exert liquid pressure directed longitudinally of the nozzle and thereby accelerating the rate of spiral advancement of a portion of this stream, the nozzle being devoid of a physical wall separating the spirally advancing jet of the liquid stream from the remaining part of said stream.
- 35 10. In a spray nozzle, a casing contracted at one end into a tapering spray-producing chamber having a forward outlet smaller than the rear end of the said chamber, and a core mounted in the casing behind the said 40 chamber, the said core having a portion shielding the outlet from the direct projection or travel of an axial portion of the initial stream therethrough, said core having a formation for imparting a plurality of different movements to different portions of the 45 said initial stream, and for uniting the said portions of liquid into a single unitary stream at the forward end of the core, the nozzle being devoid of a physical wall separating the said several portions of the said initial stream.
11. In a spray nozzle, a casing contracted at one end into a tapering spray-producing chamber having a forward outlet smaller 55 than the rear end of the said chamber, and a core mounted in the casing behind the said chamber, the said core having a portion extending across the longitudinal axis of the nozzle and shielding the said outlet from the direct projection or travel of an axial portion of the initial stream therethrough, said core having a vane or vanes with a formation for imparting a plurality of different movements to different portions of the 60 said initial stream, and for uniting the said portions of liquid into a single unitary stream at the forward end of the core, the nozzle being devoid of a physical wall separating the said several portions of the said initial stream.
12. In a spray nozzle, a plurality of helical vanes disposed for producing rotary jets advancing spirally at a given rate, and means laterally offset from the longitudinal axis of said nozzle for altering the rate of 70 spiral advancement of a portion of said rotary jets, said helical vanes having free inner edges, thereby avoiding the formation of an inner physical wall.
13. In a nozzle, a core having as one element 80 thereof an obstructing formation coaxial with the nozzle and as another element thereof, a vane disposed in substantially helical shape, one of said elements being shaped, for modifying the rate of spiral advancement imparted to the liquid by the vane, said helical vane having a free inner edge, thereby avoiding the formation of an inner physical wall.
14. In a nozzle, a core having as one element 90 thereof of an obstructing formation coaxial with the nozzle and as another element thereof, a vane disposed in substantially helical shape, one of said elements being shaped laterally offset from the longitudinal 95 axis of the nozzle for the passage of a portion of the initial liquid stream, said helical vane having a free inner edge, thereby avoiding the formation of an inner physical wall.
15. A spray nozzle having a housing provided with an inlet and an outlet, and a core within the housing having a vane or vanes affording a passage or passages and having a central obstructing formation integral 100 with said vane or vanes and also having an opening inside the outer radial limits of said vane or vanes to permit the onward projection or travel of a part of the liquid entering at said inlet, there being no physical 105 wall separating said opening from the passage or passages afforded by said vane or vanes.
16. A spray nozzle having a housing provided with an inlet and an outlet, a core 115 within the housing having a vane or vanes affording a passage or passages and having a central obstructing formation, and a mixing chamber in advance of said core and from which the liquid is discharged through 120 said outlet, and also having an opening inside the outer radial limits of said vane or vanes to permit the onward projection or travel of a part of the liquid entering at said inlet, there being no physical wall separating said opening from the passage or 125 passages afforded by said vane or vanes.
17. A spray nozzle having a housing provided with an inlet and an outlet, a core within the housing having a vane or vanes 130

- affording a passage or passages and having a central obstructing formation formed with said vane or vanes, and means in advance of said core, coöperating to cause the liquid to issue from the nozzle in a spray of substantially uniform homogeneity, and also having an opening inside the outer radial limits of said vane or vanes to permit the onward projection or travel of a part of the liquid 5 entering at said inlet, there being no physical wall separating said opening from the passage or passages afforded by said vane or vanes.
18. A spray nozzle having a housing provided with an inlet and an outlet, a core within the housing having a vane or vanes affording a passage or passages and having a central obstructing formation, said core also having a formation permitting the forward projection or travel of a portion of the liquid stream, there being no physical wall between said formation permitting said forward projection and the passage or passages afforded by said vane or vanes, and a mixing 10 chamber in advance of said core and from which the liquid is discharged through said outlet.
19. A spray nozzle having a housing provided with an inlet and an outlet, a core within the housing having a vane or vanes affording a passage or passages, and having a central obstructing formation, said core also having a formation permitting the forward projection or travel of a portion of the liquid stream, there being no physical wall between said formation permitting said forward projection and the passage or passages afforded by said vane or vanes, and means in advance of said core coöperating to cause the liquid to issue from the nozzle in a spray of substantially uniform homogeneity.
20. A nozzle having a housing with an inlet and an outlet for a liquid stream and a core within said housing, said core having formations causing different portions of a single and imperforate stream of liquid devoid of physical separating walls to impact upon each other and upon the interior of said housing, and all said portions to travel forward in paths that are non-axial of the nozzle to convert said liquid stream into a spray of substantially uniform consistency.
21. A nozzle having a housing with an inlet and an outlet for a liquid stream, and a core within said housing, said core having formations causing different portions of a single and imperforate stream of liquid to impact upon each other and upon the interior of said housing to convert said liquid stream into a spray of substantially uniform consistency, including a spiral passage and an opening laterally offset from the axis of the nozzle, the nozzle being devoid of a physical wall separating the spiral passage from said laterally offset opening.
22. A spray nozzle having a housing with an inlet and an outlet and a vane within the housing for imparting spirally advancing motion to a part of a liquid stream, said vane having a vane-edge shape or formation 70 providing a liquid passage laterally offset from the axis of the nozzle, for the forward projection or travel of a portion of the liquid stream.
23. A spray nozzle having a housing with an inlet and an outlet and a vane within the housing for imparting spirally advancing motion to a part of a liquid stream, said vane having at an inner edge a shape or formation providing a liquid passage laterally offset from the axis of the nozzle, for the forward projection or travel of a portion of the liquid stream.
24. A spray nozzle having a housing with an inlet and an outlet and a vane within the housing for imparting spirally advancing motion to a part of a liquid stream, said vane having an edge thereof provided with a shape or formation providing a liquid passage laterally offset from the axis of the nozzle for the forward projection or travel of a portion of the liquid stream, said housing having a mixing chamber in advance of said vane and from which the liquid is discharged through said outlet as a spray of substantially uniform homogeneity throughout.
25. A spray nozzle having a housing with an inlet and an outlet and a vane within the housing for imparting spirally advancing motion to a part of a liquid stream, said vane having an edge thereof provided with a shape or formation providing a liquid passage laterally offset from the axis of the nozzle, for the forward projection or travel of a portion of the liquid stream, said housing having a spray producing chamber in advance of said vane.
26. In a liquid-manipulating nozzle, means tending to produce an initial stream developing a spirally advancing jet, and means for causing a part of said stream to exert liquid pressure directed longitudinally of the nozzle but non-axially of said nozzle and thereby accelerating the rate of spiral advancement of a portion of this stream.
27. A spray nozzle having a housing provided with an inlet and an outlet, a core within the housing having a vane or vanes affording a passage or passages and having a central obstructing formation at the same height or zone in the nozzle as that of a portion of the vane or vanes which is of the full width of such vane or vanes and a formation providing a liquid passage laterally offset from the axis of the nozzle, there being no physical wall between said central obstructing formation and the passage or passages afforded by said vane or vanes, and means in advance of said core coöperating 130

to cause the liquid to issue from the nozzle in a spray of substantially uniform homogeneity.

28. A nozzle comprising a casing, a vane or vanes therein to impose a spirally advancing motion upon a part of the stream entering the nozzle, the vane having an edge formation laterally of the axis of the nozzle to modify the flow of said part of the stream and to co-act in effecting the discharge of the stream in a spray that is substantially uniform or homogeneous.

29. A spray nozzle having a housing with an inlet and an outlet, and means within the housing for imparting a spirally advancing motion to parts of a liquid stream, said means having a formation providing for forward, non-spiral passage of a part of the liquid stream laterally of the axis of the nozzle, and to mingle with the first mentioned part of the liquid stream but devoid of physical separating wall and to co-act in effecting the discharge of the stream in a spray that is of substantially uniform homogeneity.

30. A spray nozzle having a housing with an inlet and an outlet, and means within the housing for imparting a spirally advancing motion to parts of a liquid stream, said means having a formation providing for forward, non-spiral passage of a part of the liquid stream laterally of the axis of the nozzle, and to mingle with the first mentioned part of the liquid stream but devoid of physical separating wall and to co-act in effecting the discharge of the stream in a spray that is of substantially uniform homogeneity, the nozzle having a mixing chamber in advance of said vane or vanes and which co-operates in effecting the discharge of the spray in a substantially uniform or homogeneous condition.

31. A nozzle comprising a casing, a vane or vanes therein to impose a spirally advancing motion to a part of the stream entering the nozzle, the vane having a formation laterally of the axis of the nozzle to modify the flow of said part of the stream but devoid of physical separating wall and to co-act in effecting the discharge of the stream in a spray that is substantially uniform or homogeneous, the nozzle having a mixing chamber in advance of said vane or vanes and which co-operates in effecting the discharge of the spray in a substantially uniform or homogeneous condition.

32. A nozzle comprising a casing, a vane or vanes therein to impose a spirally advancing motion upon a part of the stream entering the nozzle, the vane having a formation laterally of the axis of the nozzle to modify the flow of the said part of the stream and to co-act in effecting the discharge of the stream in a spray that is substantially uniform or homogeneous, the nozzle being de-

void of a physical wall separating the spirally advancing part of the stream from the remainder thereof.

33. A spray nozzle having a housing with an inlet and an outlet and a core within the housing having a vane or vanes and also having a vane-edge formation laterally of the axis of the nozzle providing in effect a bore extending along the nozzle core in a direction substantially parallel to the axis of the core.

34. A spray nozzle having a housing with an inlet and an outlet and a core within the housing having a vane or vanes and also having a vane-edge formation laterally of the axis of the nozzle providing in effect a bore extending along the nozzle core in a direction substantially parallel to the axis of the core, the nozzle having a mixing chamber in advance of said core.

35. A spray nozzle having a housing provided with an inlet and an outlet, and a core within the housing having a plurality of vanes imparting a spirally advancing motion to a part of the liquid stream entering the nozzle, the core having a vane-edge formation laterally of the axis of the nozzle providing in effect a bore permitting the forward passage of a portion of the liquid stream in a direction substantially parallel to the axis of the core, the nozzle having a mixing chamber in advance of the core in which the several parts of the stream are mixed and from which mixing chamber they issue in a spray of substantially uniform homogeneity.

36. A spray nozzle comprising a casing and a core within the casing co-operating with the latter for initially imparting spirally advancing motion to parts of a liquid stream, said core having a formation laterally of the axis of the core for altering the motion of a portion of each of said parts, thereby causing these to blend into an impure stream subject to a variety of different strains, there being no physical wall between the spirally advancing parts of the liquid stream and the remainder thereof.

37. In a liquid manipulating nozzle, means tending to produce from an original stream a spirally advancing jet, and means laterally of the axis of the nozzle for causing a part of the original stream to exert liquid pressure directly longitudinally of the nozzle, and thereby accelerating the rate of spiral advancement of a portion of such jet.

38. A spray nozzle having a housing provided with an inlet and an outlet, a core within the housing having a vane or vanes and having a central obstructing formation integral with said vane or vanes, said core having an edge formation of at least one of its vanes laterally of the axis of the core, permitting forward movement of a part of

the liquid stream laterally of the axis of the core, said nozzle having a mixing chamber in advance of the core wherein the several parts of the liquid stream meet and 5 from which the liquid issues in a spray of substantially uniform homogeneity.

39. A spray nozzle having a housing with an inlet and an outlet and a vane within the housing for imparting spirally advancing 10 motion to a part of a liquid stream, said vane having a vane-edge shape or formation providing a passage laterally offset from the axis of the nozzle for the forward projection or travel of a portion of the liquid stream. 15

40. A nozzle comprising a casing, a vane or vanes therein to impose a spirally advancing motion upon a part of the stream entering the nozzle, and having a formation laterally of the axis of the nozzle to modify 20 the flow of said part of the stream and to coact in affecting the discharge of the stream in a spray that is substantially uniform or homogeneous, there being no forward projecting physical wall between said 25 formation and the passage or passages afforded by said vane or vanes.

In testimony whereof, I have signed my name to this specification.

LEE H. PARKER.
